US00D965062S

(12) **United States Design Patent** (10) **Patent No.:** **US D965,062 S**
Wu (45) **Date of Patent:** **** Sep. 27, 2022**

(54) **LUGGAGE TAG**

(71) Applicant: **HENAN TESIKAI NETWORK TECHNOLOGY CO., LTD.**,
Zhengzhou (CN)

(72) Inventor: **Caili Wu**, Yueyang (CN)

(73) Assignee: **HENAN TESIKAI NETWORK TECHNOLOGY CO., LTD.**,
Zhengzhou (CN)

(**) Term: **15 Years**

(21) Appl. No.: **29/791,406**

(22) Filed: **Jan. 10, 2022**

(51) **LOC (13) Cl.** **19-08**

(52) **U.S. Cl.**
USPC **D20/27**

(58) **Field of Classification Search**

USPC D3/247-249; D20/22-27
CPC G09F 2003/0254; G09F 2003/0255; G09F
2003/0251; G09F 3/14; G09F 3/185

See application file for complete search history.

Primary Examiner — Catherine Ho

(57) **CLAIM**

The ornamental design for a luggage tag, as shown and described.

DESCRIPTION

FIG. 1 is a top perspective view of a luggage tag showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dotted broken lines represent stitching that forms part of the claimed design. The dashed broken lines depict portions of the article that form no part of the claimed design.

1 Claim, 8 Drawing Sheets
